UNITED STATES PATENT OFFICE.

HARRY C. INNES, OF HARTWELL, OHIO, ASSIGNOR OF ONE-HALF TO THE FRANKLIN COTTON MILL COMPANY, OF CINCINNATI, OHIO, A CORPORATION OF OHIO.

MATTRESS.

No. 877,568.

Specification of Letters Patent.

Patented Jan. 23, 1908.

Application filed June 17, 1907. Serial No. 379,482.

To all whom it may concern:

Be it known that I, HARRY C. INNES, a citizen of the United States, and a resident of the town of Hartwell, in the county of Hamilton and State of Ohio, have invented certain new and useful Improvements in Mattresses, of which the following is a specification.

The several features of my invention and the various advantages resulting from their use conjointly or otherwise will be apparent from the following description and claims.

In the accompanying drawings making a part of this specification, and in which similar letters of reference indicate corresponding parts, Figure 1 is a plan view of a mattress illustrating certain features of my invention. Fig. 2 is a view in perspective of the same mattress folded. Fig. 3 is a view of a portion of the said mattress and illustrating certain features of the woven stitch. Fig. 4 is an enlarged view of the stitching looking across the warp, that is looking at the side of the lengths of the warp. Fig. 5 is an enlarged view of the stitching looking across the woof, that is, looking at the side of the lengths of the woof.

The stitch is one adapted and contrived for a stock of thickness, elasticity and flexibility. In the preferred grade of this stock, there are several plies P. In connection with each woof, the warp B goes in pairs, that is the warp consists of two strings or thick threads B, B. Each pair of strings always goes together, and such pair goes under one woof A and over the next woof A, then over the next woof A, and so on, going alternately under one woof and over the next woof to the end of the stock or piece. The adjacent pair of strings goes over one woof and under the next woof and under the next woof until the end of the stock is reached. That is to say, that in describing the direction in which the pairs of strings (the warp) go, at a given woof, the pair of strings (one warp) goes under a given woof, when the adjacent pair of strings (warp) goes over this woof. Thus in following a given woof, it will be seen that one pair of strings goes over and the next pair of strings goes under this woof; and the next pair of strings goes over, and so on, going alternately under and over the woof until the side edge of the stock is reached.

There are several layers (preferably six) of plies (of warp thread), one below the other.

Each ply of woof consists of nine plies in one body slightly twisted. Such plies are respectively represented by the respective lines B of the Fig. 3. There are binding threads called binders C to hold the different layers of the fabric, each of which layers consists in the first instance of an interwoven texture of warp and woof. These binders start from one side of the compacted mass of said layers and extend through the said mass to the other side. They go up on one side of those plies of woof which are in the same vertical plane and down on the other side of this set of plies. These binders from another point of view pass up between two vertical sets of warps and over one of these sets and down between this set and the one adjacent, and so on, see Fig. 3.

The mattress may be made in one piece, but where the bed is wide the mattress consists of two parts X and Y, each the counterpart of the other. For example, the part X is at its outer side and at its head and foot end bound with a suitable binding Z and S; also the part Y is similarly bound with a similar binding Z. At their adjacent edges the parts X and Y are not bound with a binding, but the weaving forms a closed edge. These two parts X and Y of the mattress are suitably connected, preferably by a mode known as whip stitching, a binding cord T, which permits them to be folded upon each other when the occasion requires. The mattress thus becomes very portable.

Among the various advantages to be noted, as resulting from my invention, are the following: In a mattress made as described, no fitting is required and no lumps are present, as a result of refitting. The mattress is a very convenient one to be furnished as an article of commerce. There is no roughness in the mattress, but the very slight inequalities present and slightly felt in passing the hand over the mattress act advantageously as a very gentle massage to the skin. This mattress is pliable. It is resili-ent and at the same time, in use it does not pack hard, as is the case with the cotton and hair stuffing in the common stuffed mattress. All tufts and tufting are avoided. Consequently, no lumps are present on the mattress to hurt the body of the occupant.

This mattress is thoroughly sanitary, because it can be readily scrubbed, washed and cleaned. It withstands the wear of such

cleansing operations exceedingly well. The air can pass through the mattress thus cleansing it of impurities and also assisting in carrying away the odors of the body emanating from the one occupying the mattress.

Another improvement of my invention consists as follows: The binding S does not stop at the edge of the one part X, but is continued on along the edge of the part Y. Thus 10 the binding is continuous along the edges of the mattress. When the mattress is folded, the binding readily flexes at the places S¹, S². The rest of the mattress folds readily without kinking at the line of junction of the 15 whipped stitching T.

When desired, the mattress, if very long, is to be made of three parts, interconnected in the manner described. The purer air of the room has better opportunity to reach the 20 occupant of the couch on account of the character of this mattress. The mattress is sufficiently flexible to be rolled, when occasion requires. The portability of this mattress also admits of its being readily put upon a 25 clothes line.

What I claim as new, and of my invention and desire to secure by Letters Patent, is:—

1. A woven mattress composed of several 30 ply thicknesses of fabric, bound at the edges, and made in two parts connected by a whipped stitch hinge, and adapted, the one part to fold upon the other, substantially as and for the purpose specified.

2. A compact elastic mattress, consisting 35 of a textile fabric, of several plies, the warp consisting of two threads, and the woof threads wound in and back, the several plies held together by the tying cords or threads passing each other in opposite directions between each line of woof, and holding the entire fabric in a compact elastic condition, this 40 mattress composed of two parts bound at the outer edges, woven not to unravel at their adjacent edges, and connected by a flexible cord connection, substantially as and for the purposes specified.

3. A compact elastic mattress, consisting of a textile fabric of several plies, the warp 45 consisting of two compressible cotton threads, and the woof threads wound in and back, the several plies held together by the tying cords or threads passing each other in opposite directions between each line of woof, and holding the entire fabric in a compact elastic condition, substantially as and for the purposes specified.

4. A compact elastic mattress, consisting of a textile fabric, of several plies, the warp 55 consisting of two compressible cotton threads, and the linen woof threads wound in and back, the several plies held together by the tying cords or threads passing each other in opposite directions between each line of woof, 60 and holding the entire fabric in a compact elastic condition, substantially as and for the purposes specified.

5. A compact elastic mattress, consisting of a textile fabric of several plies, the warp 65 consisting of two threads, and the woof threads wound in and back, the several plies held together by the tying cords or threads passing each other in opposite directions between each line of woof, and holding the entire fabric in a compact elastic condition, this 70 mattress composed of two parts bound at the outer edges, woven not to unravel at their adjacent edges, and connected by a flexible cord connection, substantially as and for the purposes specified.

6. A woven mattress, composed of several 75 ply thicknesses of fabric and made in parts, these parts connected by a cord hinge, and at the outer edges bound and connected together 80 by a continuous flexible binding, substantially as and for the purposes specified.

HARRY C. INNES.
